UNITED STATES PATENT OFFICE

JESSE E. ESHBAUGH, OF FLINT, MICHIGAN, ASSIGNOR TO A C SPARK PLUG COMPANY, OF FLINT, MICHIGAN, A COMPANY OF MICHIGAN

AMMETER

Application filed September 22, 1927. Serial No. 221,313.

This invention relates to ammeters and particularly to ammeters of the type ordinarily mounted on the dashboard of an automotive vehicle.

5 Ammeters of this type ordinarily include a section of a conductor through which the current to be measured passes, a pivotally mounted armature carrying an indicating needle, a dial, and a permanent magnet placed to hold the armature parallel with 10 a section of the conductor. A difficulty encountered with such a structure is that as a current passes through the conductor, the armature is moved from a position perpendicular to a tangent to the lines of force (assuming the conductor to be substantially 15 round in section) to a position at an obtuse angle to the tangent at the point at which the armature passes through the lines of force. Hence the deflection of the armature for each successive unit of current is progressively less. To compensate for this the 20 divisions on the scale must increase from zero in either direction.

25 It is an object of this invention to remove as far as possible the highly congested scale which is generally characteristic of an ammeter of this class and to secure a certain amount of pointer "damping".

30 I accomplish this result by so shaping the conductor that as the armature rotates it moves into a magnetic field of progressively increasing intensity per unit of current.

Other objects of the invention will appear 35 in the course of the following description, taken in connection with the accompanying drawing and appended claims.

In the drawing:

Figure 1 is a vertical longitudinal section 40 of the device.

Figure 2 is a section on the line 2-2 of Figure 1, with parts broken away.

Figure 3 is a section on the line 3-3 of Figure 1.

45 Figure 4 is a section on the line 4-4 of Figure 3.

Figure 5 is a vertical longitudinal section of a modified form of my invention.

50 Figure 6 is a section on the line 6-6 of Figure 5.

Figure 7 is a diagrammatic view taken in a vertical transverse plane and illustrating the direction of the lines of force from the permanent magnet and the conductor.

55 Figure 8 is a separated view of the connection between the pointer, shaft and armature.

Referring to the drawing the numeral 10 indicates the usual cup-shaped case, flanged at its rim and provided in its rear face with 60 apertures for the reception of the terminal bolts. Fixed to the rear face of the case is the conductor frame 11 through which passes the current to be measured. In the embodiment illustrated in Figures 1 to 4, the conductor frame 11 comprises two similar oppositely disposed brackets or side members 12 and a central bridge member 14, the parts being fixed together by bent down portions or lugs 16 on central member 14. Each 65 bracket or side member 12 has one end bent at right angles to form a foot 13 which is provided with an up-turned end 18 for fitting against the straight side of the head 20 of the terminal bolt 21. The opposite ends 17 of 70 the brackets 12 are flanged or turned away from the main or central portion thereof to form a seat for the bridge member 14. The ends of the flanged portions 17 are in turn 75 bent as at 19. The side member 12 is held by the terminal bolt 21 against the rear face of the case by means of the nut 26. The frame 11 is spaced from the casing by a strip 22 of insulating material, and an insulating washer 24 is placed between the nut 26 and 80 the casing.

The inner adjacent portions of the side members 12 have walls 30 which are arcuate in shape. The arcuate walls 30 of the brackets 12 are preferably though not necessarily portions of the same cylindrical surface as is seen in Figures 2, 3, and 6. The central bridge member 14 is provided with a rearwardly bent portion 32, the end 33 of which extends under the mid-portion of the 85 bridge 14. The opposed faces of the end 33 of the bridge 14 are prick punched to provide bearings for the cone-shaped ends 31 of the shaft 34 on which is mounted a needle 38 and an armature 36 of magnetic metal. The ar- 90 95 100

mature is mounted on the shaft by means of parallel slits or openings 35 and 37 as illustrated, the tension of the metal holding it in position without other fastening means. As shown in Figures 1 and 8, the needle extends around the shaft and has a portion 39 which extends downwardly and then rearwardly and is held between the shaft and a portion of the armature. This arrangement provides means for quickly assembling the needle and armature on the shaft, the tension of the metallic armature being sufficient to insure that the parts will be held firmly in position. This arrangement avoids the necessity of using collars, bushings or wax to hold the needle and armature on the shaft. The shaft on which the armature and needle are mounted is centrally disposed with relation to the arcuate portions 30 of the side members 12.

Fitting against the conductor frame and held against movement relative thereto by means of bent up portions or lugs 40 of the bridge 14 of the coconductor frame is the permanent magnet 42. Extending over the magnet is the dial 44. The dial, magnet and conductor frame are held together by rivets 46. The dial is provided with an arcuate slot 48 through which passes the offset portion 49 of the indicating needle 38. The usual glass cover 50 and bezel 52 are provided for making the case dustproof.

In the modification shown in Figures 5 and 6 the conductor frame 11' is formed of a single sheet of metal, pressed into the shape described above. The frame 11' in this species comprises the cup-shaped central portion having the bottom 14' and the arcuate sides 30', and the flanged extensions 17'. The cup bottom 14' has the finger 60, which is preferably integral, bent to have its end 33' extend under the central or mid portion of the cup bottom 14'. The magnet 42 and dial 44 are mounted on the bottom 14' in any suitable way. With these exceptions, the structure of this modification is the same as that of the embodiment disclosed in Figures 1 to 4, except for slight changes in dimensions.

In Figure 7 I have illustrated diagrammatically the magnetic field with a current passing through the conductor. The lines A of the permanent magnet extend from left to right and, in the absence of a current through the conductor, hold the armature in the position illustrated. The magnetic flux B about the curved portions of the conductor resulting from the passage of current is substantially at right angles to the plane of the armature as illustrated and tends to swing it about its axis to a position at right angles to its illustrated position. As the gap between the two curved sections of the conductor is greater at the center, or through the plane of the armature as illustrated in Figure 7, than at

the edges, the magnetic field about the curved walls 30 or a given current passing therethrough is less intense at the center than at the adjacent edges of the arcuate portions. This is illustrated by the wider spacing of the curved vertical lines of force at the center. As the armature rotates it moves into a space where the distance between the two curved sections of the conductor is less and hence the component magnetic flux per unit of area is greater. This factor compensates for the normal lessening of the deflection ordinarily occurring as the armature moves away from dead center position and permits the use of a scale with less congestion of graduations on the dial. The magnetic flux about the connecting or center portion 14 also aids in deflecting the armature. The dial is graduated in the usual way to indicate the position of the needle 38.

Mounting the flat armature to swing about an axis which lies in its own plane instead of perpendicular thereto and providing a cup-shaped conductor nearly surrounding the armature produces an ammeter which is very well "damped," this construction being quite insensitive to vibrations of the machine.

I claim:

1. In an ammeter, a permanent magnet, an armature pivotally mounted adjacent thereto, and a conductor adjacent the armature, the surface of the conductor adjacent the armature being substantially concentric with the axis thereof.

2. In an ammeter, a conductor comprising side portions and a connecting portion, said side portions being farther apart at the center than at the edges, an armature of magnetic material pivotally mounted between said side portions, and a permanent magnet mounted adjacent thereto in position to hold said armature in line with the widest spaced parts of the side members.

3. In an ammeter, a conductor comprising parallel portions and a connecting portion, said parallel portions being closer together at their edges than at their centers, an armature of magnetic sheet material mounted on a shaft parallel with and between the side portions, and a permanent magnet mounted adjacent said conductor.

4. In an ammeter, a conductor comprising two substantially concentric diametrically opposed cylindrical sections and a connection therebetween, an armature of magnetic material pivotally mounted on a shaft concentric with said sections, and a permanent magnet adjacent said armature.

5. In an ammeter, a conductor having two spaced walls, a pointer swinging shaft pivotally mounted between said walls, an armature mounted on said shaft, and means to bias said armature and pointer to zero position.

6. In an ammeter, a casing, a pair of brack-

ets secured in the casing, said brackets including spaced walls, a bridge piece connecting the walls, said brackets and bridge piece forming a conductor, a pointer swinging shaft pivotally mounted between said brackets, an armature mounted on said shaft, and a magnet to bias said pointer to zero position.

5 7. The structure of claim 6, said magnet secured to said bridge member.

10 8. The structure of claim 6, said brackets having flanged extensions to which said bridge piece is connected.

15 9. The structure of claim 6, and a finger on said bridge, said finger extending under the main portion of the bridge with the bridge serving to mount the shaft.

20 10. The structure of claim 6, a dial over said bridge and magnet, and means passing through said dial, bridge and magnet to hold the parts in rigid relation.

25 11. In an ammeter, a conductor having spaced arcuate walls, a pointer swinging shaft pivotally mounted between said walls, an armature mounted on said shaft, and means to bias said armature and pointer to zero position.

30 12. In an ammeter, a conductor having spaced arcuate walls each forming a part of the same cylindrical surface, a pointer swinging shaft pivotally mounted between said walls, an armature mounted on said shaft, and means to bias said armature and pointer to zero position.

35 13. In an ammeter, a casing, a pair of brackets secured in the casing, said brackets including spaced walls, a bridge piece connecting the walls, said brackets and bridge piece forming a conductor, a pointer swinging shaft pivotally mounted between said brackets, an armature mounted on said shaft, a magnet to bias said pointer to zero position, and integral lugs on said bridge piece to retain said magnet.

40 14. In an ammeter, a casing, a pair of brackets secured in the casing, said brackets including spaced walls, a bridge piece connecting the walls, said brackets and bridge piece forming a conductor, a pointer swinging shaft pivotally mounted between said brackets, an armature mounted on said shaft, a magnet to bias said pointer to zero position, and feet on said brackets by means of which said brackets are secured to the casing.

45 55 In testimony whereof I affix my signature.
JESSE E. ESHBAUGH.
